UNITED STATES PATENT OFFICE

2,510,813

PIPE ROTATING TONGS

William E. Gean, Good Pine, La.

Application June 1, 1948; Serial No. 30,379

3 Claims.

(Cl. 255—35)

1

This invention relates to a device for rotating a section of an oil well pipe to engage said section threadedly with another pipe section, or to disengage it from the other section, as desired.

It is well known that the threading or unthreading of oil well pipe sections by the method most usually employed, involving the use of a fast turning "cat head" and spinning line in making up pipe required for drilling and producing wells, creates hazardous working conditions. Serious accidents have occurred, and need has been recognized in the art for a means for screwing or unscrewing the pipe sections which will eliminate the dangerous aspects of this operation.

It has accordingly been the main purpose of the present invention to devise a machine that will eliminate or reduce greatly the possibility of accident in making up or disassembling pipe at the site of a drilling or producing oil well.

Other important objects are to provide a device of this character that can be easily positioned at a desired location; that is readily applied to a pipe section for threading or unthreading thereof, and as readily removed; will be durable and efficient in operation; can receive its power from equipment already located at the well site; and that can be constructed at relatively low cost.

To this end, I provide a device of the character described that can be readily connected to the motor on the oil well servicing unit which is standard equipment at the well. The machine includes a shaft housing in which is journaled a shaft driven by the motor. Through the medium of a clutch arrangement, a driving connection is made or broken as desired between the shaft and a pinion that extends into an annular casing rigid with the shaft housing. The casing contains a ring gear powered by the pinion, and a plurality of gripping segments rotatable with the ring gear, and mounted to be moved radially into gripping engagement with a pipe section surrounded by the casing. The casing, ring gear, and gripping means are split diametrically to provide opposed halves. These halves are hinged together so that the casing can be applied to or removed from the pipe section, and a latch arrangement is utilized to hold the halves together around the pipe when the machine is in use. The device is capable of being inverted, and when

inverted, uncouples the pipe section to which it is applied, from an adjacent pipe section.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Figure 1 is a plan view of a pipe rotating tongs constructed in accordance with the invention, portions being broken away.

Figure 2 is a view partly in side elevation and partly in longitudinal section.

Figure 3 is an enlarged section through the casing, taken substantially on line 3—3 of Fig. 1.

Figure 4 is a perspective view of one of the gripping segments.

Figure 5 is an enlarged view partly in elevation and partly in transverse section of one of the ring gear bearings.

Figure 6 is a bottom plan view of said bearing.

Referring to the drawings in detail, a shaft 7 is driven from the motor (not shown) required for regular well operations, through the medium of a universal joint 8. Obviously, any number of universal joints can be used as required, as well as shafting, either telescoping or otherwise, extending between said joints. These have not been illustrated, because such driving arrangements are well known, and it is necessary to note in the present instance only that a suitable driving connection is made between the motor and shaft 7, at the location where the machine is to be used.

Shaft 7 rotates in a bearing 9 mounted in a cylindrical shaft housing 10, and keyed to the end of the shaft for sliding movement thereon is a frusto-conical clutch member 11. The splined clutch, through the use of an operating handle 12 pivoted to the shaft housing 10, is selectively positioned so as to engage or disengage a cooperating clutch member 13 that rotates a stub shaft 14 carrying the beveled pinion 15. Pinion 15 extends into an annular casing generally designated 16, and comprising the casing members 17 and 18 hingedly connected as 50 at 19. The shaft housing 10 is rigidly connected

to one of these members, in the present instance the casing member 18.

Carried by the casing members 17 and 18 respectively are handles 20 and 21 whereby the members can be swung apart or together as desired. The casing member 18 carries the pivoted spring pressed latch 22 engageable with the tooth 23 of the member 17. Thus, when the members are brought together as illustrated in Fig. 1, the cooperating latch portions engage to provide what is in effect a rigid annular casing adapted to surround an oil well pipe section, not shown.

Mounted for rotation in the casing is the split ring gear comprising the gear member 24 and the gear member 25. Each of these extends through a half circle, so that when the casing members are brought together as in Fig. 1, the gear members cooperate to provide the ring gear.

Formed in the outer surfaces of the gear members 24 and 25 are peripheral grooves 26 cooperating to define a single annular groove receiving the pinion 15. In the opposed faces of the gear member 24 are formed bearing grooves 27, and in the opposed faces of the gear member 25 are similar bearing grooves 28. These receive roller bearings 29 connected to the casing by means of fastening means 30.

Gear teeth 31 are formed on one side wall of the pinion-receiving groove of the ring gear, and thus it will be seen that assuming the casing members are latched together as in Fig. 1 and that the clutch members are engaged, power transmitted to shaft 7 will in turn result in rotation of the compositely formed ring gear.

When the casing members 17 and 18 are latched, they define a pipe-receiving center opening 32. This opening is partially closed by inwardly extended top and bottom flanges 33 of the gear member 24, and inwardly extended top and bottom flanges 34 of the gear member 25.

Registering openings 35 are formed in the flanges, receiving bolts 36 that extend through angularly disposed slots 37 provided in arcuate gripping segments 38, having their inner surfaces toothed for gripping engagement with a pipe section as best shown in Fig. 4. The number of gripping segments 38 can vary, but in the present instance, and preferably, four are illustrated, each extending through approximately 90°. The segments are housed between the flanges 33 and between the flanges 34. The segments, as will be observed, are readily removable, so as to accommodate different pipe diameters.

By reason of the fact that the respective slots 37 are tangent to a circle having its center on the axis of rotation of the ring gear, said slots will be oblique to the circular path through which the bolts 36 move. Considering now the manner in which the segments function, the segments will first have been brought into engagement with the pipe by the swinging together and latching of the casing sections. Then the motor is started, and the initial rotatable movement of the bolts results in said bolts bearing against the inner walls of the slots, so that the segments are biased radially and inwardly into a tight gripping engagement with the pipe section to be rotated, as a result of which the ring gear, segments, and pipe rotate as one. Thus, the pipe section is threaded upon another pipe section. Through the simple medium of inverting the device, said pipe section is unthreaded from a pipe section to which it has been previously connected. The machine is thus adapted for threading or disconnecting operations as necessary.

To suspend the machine in proper position to grip a pipe section, there may be provided a yoke 39 pivoted to the casing 16, to which yoke would be connected a cable, not shown, secured to some portion of the well structure.

In practice, the tongs are operated by a worker controlling the clutch. Assuming that a pipe is being threaded connected to another pipe, indication that the threaded engagement has been completed is provided by utilizing a torque wrench, which provides this indication by a noise which is familiar to the worker.

What is claimed is:

1. Pipe rotating mechanism including an annular casing comprising hingedly connected casing members; means releasably holding the members against separation; a ring gear formed in separate sections and mounted for rotation in the casing, there being an annular channel in the inner surface of the ring gear; a group of segments seated in said channel and having toothed inner portions extended inwardly beyond the channel into engagement with a pipe to be rotated, each segment having a cam slot disposed obliquely to the path of rotation of the ring gear; bolts extending between the walls of the channel and through the slots and removably connecting the segments to the ring gear, said bolts bearing against the inner walls of the slots on rotation of the ring gear to bias said segments inwardly into gripping engagement with said pipe; and means for driving the ring gear.

2. Pipe turning mechanism including an annular casing comprising hingedly connected casing members; means releasably holding said members against separation; a ring gear formed in sections and mounted for rotation in said casing, the inner surface of said ring gear being formed with a channel; a plurality of arcuate segments seated in said channel and having their inner surfaces extended inwardly beyond the channel, said inner surfaces of the segments being toothed for engagement with a pipe to be rotated, each segment having a slot disposed obliquely to the path of rotation of said ring gear and said segments being normally spaced apart at their ends; bolts removably mounted in the walls of said channel and extending across the channel and through the respective slots for removable connection of the segments to the ring gear, said bolts bearing against the inner walls of said slots to bias the segments inwardly toward the pipe while rotating the segments with the ring gear; and means for driving said ring gear.

3. Pipe turning mechanism comprising an annular casing including a pair of semi-circular channeled casing members hingedly connected at one end; latch means for releasably connecting the other ends of said members to form an annular casing surrounding a pipe to be rotated; bearing rollers mounted in the walls of said channeled casing; a ring gear rotatably mounted in said channeled casing and having its opposite faces grooved to receive said bearing rollers, the inner surface of said ring gear being formed with a channel; a plurality of arcuate segments seated in said channel and having their inner surfaces extended inwardly beyond the channel, said inner surfaces of the segments being toothed for engagement with a pipe to be rotated, each segment having a slot disposed obliquely to the path of rotation of said ring gear and said segments being normally spaced apart at their ends; bolts

removably mounted in the walls of said channel and extending across the channel and through the respective slots for removable connection of the segments to the ring gear, said bolts bearing against the inner walls of said slots to bias the segments inwardly toward the pipe while rotating the segments with the ring gear; and means for driving said ring gear.
